US00D889508S

(12) United States Design Patent (10) Patent No.: US D889,508 S
Kane et al. (45) Date of Patent:  Jul. 7, 2020

(54) DISPLAY SCREEN OR PORTION THEREOF WITH A GRAPHICAL USER INTERFACE

(71) Applicant: Beijing Microlive Vision Technology Co., Ltd., Beijing (CN)

(72) Inventors: Travis Kane, Los Angeles, CA (US); Hui Sun, Shanghai (CN); Michael Martinho, Beverly Hills, CA (US); Raffi Baghoomian, Los Angeles, CA (US)

(73) Assignee: BEIJING MICROLIVE VISION TECHNOLOGY CO., LTD., Beijing (CN)

() Term: 15 Years

(21) Appl. No.: 29/673,884

(22) Filed: Dec. 18, 2018

Related U.S. Application Data

(63) Continuation of application No. 29/651,478, filed on Aug. 17, 2018, now Pat. No. Des. 870,140.

(51) LOC (12) Cl. 14-04

(52) U.S. Cl.

USPC D14/488; D14/485

CLAIM

We claim the ornamental design for a display screen or portion thereof with a graphical user interface, as shown and described.

DESCRIPTION

The FIGURE is a front view of a display screen or portion thereof with a graphical user interface showing our new design.

The broken lines shown in the FIGURE represent portions of the display screen or portion thereof with a graphical user interface that form no part of the claimed design.

1 Claim, 1 Drawing Sheet
